UNITED STATES PATENT OFFICE

91,330

DESIGN FOR A BROOCH

Walter S. Robertson, Attleboro, Mass., assignor to Frank S. Land, Kansas City, Mo.

Application May 29, 1933. Serial No. 48,230

Term of patent 14 years

To all whom it may concern:

Be it known that I, WALTER S. ROBERTSON, a citizen of the United States, residing at Attleboro, in the county of Bristol and State of Massachusetts, have invented a new, original, and ornamental Design for Brooches, of which the following is a specification, reference being had to the accompanying drawing forming part thereof.

Fig. 1 is a front elevation of a brooch showing my new design.

Fig. 2 is a side elevation of the same.

I claim:

The ornamental design for a brooch, as shown.

WALTER S. ROBERTSON.
